UNITED STATES PATENT OFFICE.

DAVID F. STAUFFER, OF YORK, PENNSYLVANIA.

DESIGN FOR A BISCUIT OR CRACKER.

SPECIFICATION forming part of Design No. 18,580, dated August 28, 1888.

Application filed February 7, 1887. Serial No. 236,879. Term of patent 14 years.

To all whom it may concern:

Be it known that I, DAVID F. STAUFFER, a citizen of the United States, residing at York, in the county of York and State of Pennsylvania, have invented and produced a new and original Design to be Used for Biscuits or Biscuit-Crackers, of which the following is so full, clear, and exact a description and specification as will enable others to understand my invention, reference being had to the accompanying drawings to illustrate my invention.

Figure 1 is a top view of one of my crackers or biscuits made according to my design. Fig. 2 is a perspective view of one of my crackers.

15 The illustration represents an oval design, which is provided on its outer rim with a series of notches or serrations. On its opposite side is a recess, which has a smooth edge or boundary, *a*. Between the inner smooth edge which 20 bounds the depression and the outer serrated edge which surrounds the outer portion of the

biscuit I show a second ragged or zigzag line, *b*, which extends along the biscuit midway between the rough and smooth lines heretofore described.

25 What I claim as my invention, and what I desire to secure by this patent, is—

The hereinbefore-described design for biscuits and crackers, which consists of a biscuit or cracker having two rows of serrations or 30 corrugations, one of which extends around a portion of its edge, and the other row being shorter and extending over the top and within the line of the edge of the biscuit, substantially as shown and described.

35 In testimony that I claim the above as my invention I hereunto set my hand in the presence of two witnesses.

DAVID F. STAUFFER.

Witnesses:

BETH BATTLES BARBER,
CHAS. E. BARBER.
